EDWARD E. ANSON.

By *J. Andrew Jr.* Attorney

UNITED STATES PATENT OFFICE.

EDWARD E. ANSON, OF CLARKSVILLE, OHIO.

ADJUSTABLE GATE.

Application filed October 27, 1920. Serial No. 419,883.

To all whom it may concern:

Be it known that I, EDWARD E. ANSON, a citizen of the United States, residing at Clarksville, in the county of Clinton and 5 State of Ohio, have invented certain new and useful Improvements in an Adjustable Gate; and I do hereby declare the following to be a full, clear, and exact description of the invention, such as will enable others 10 skilled in the art to which it appertains to make and use the same.

The object of the invention is to provide a gate for farm and other use which while being constructed mainly of wood is not 15 open to the objections ordinarily offered to the use of that material in the matter of warping, sagging and deterioration by rotting due to the lack of ventilation and the retention of moisture after a rain; and a 20 further object is to provide a gate which may be readily adjusted longitudinally and vertically to insure a proper and effective operation thereof; and with these objects in view the invention consists in a construction and combination of parts of which a 25 preferred embodiment is shown in the accompanying drawings, wherein—

Figure 1 is a side view of the gate.

Figure 2 is a plan view thereof.

Figure 3 is a transverse vertical section on the plane indicated by the line 3—3 of Figure 1.

Figure 4 is a similar section on the plane indicated by the line 4—4 of Figure 1.

Figure 5 is a similar section on the plane indicated by the line 5—5 of Figure 1.

Figure 6 is a detail section on the plane indicated by the line 6—6 of Figure 1.

Figure 7 is a detail view of the upper 40 hinge bar.

Figure 8 is a similar view of the lower hinge bar.

Figure 9 is a similar view of the upper hinge bar trip or lift.

The body portion of the gate, which swings between the latch post 10 and the hinge post 11 is composed of longitudinal slats or boards 12 and transverse tie bars 13, the latter also being of wood, if desired, and

50 being relatively narrow to cover the minimum surfaces of the boards to allow ample opportunity for the quick drying of the surfaces of the latter after a rain, the rider board 14 being arranged upon the upper edge of the upper marginal board 12 and the tie bars and boards being secured to-

gether by transverse bolts 15. The tie bars may be arranged in pairs of which the members are arranged at opposite sides of the plane of the boards or runners 12 to afford 60 added strength, and diagonal metallic braces 16 and 17 may be arranged as shown, the former between two intermediate sets or pairs of tie bars near the free end of the gate and the latter extending from an intermediate, as for example the central tie bar to the marginal tie bar at the hinged end of the gate structure. 65

The upper and lower hinge pins 18 and 19 are carried by the hinge post and may 70 be of any preferred construction and in engagement respectively therewith are the eyes at the adjacent ends of the upper and lower hinge bars 20 and 21. The upper hinge bar extends between the tie bars at the hinged 75 end of the gate and is seated in a notch 22 formed in a guide plate 23 which is arranged transversely of the gate to span the interval between the tie bars, said upper hinge bar extending preferably to the center of the 80 length of the gate and being provided in its underside with a series of notches 24 for selective engagement with an anchor pin 25 arranged transversely between the tie bars at the center of the gate, said anchor pin 85 also serving in the construction illustrated as the means for securing the upper rear end of the brace 16 to said tie bars.

At an intermediate point the upper hinge bar extends through a looped keeper 26 of 90 which the legs pass through one of the tie bars and are engaged by nuts 27. Said keeper serves to hold the intermediate portion of the upper hinge bar in proper relation with the other elements of the gate and prevent sagging thereof while a cross pin or bolt 28 by which the upper rear end of the brace 17 is secured to the tie bars at the hinged end of the gate extends over the upper edge of the hinge bar 20. 95

The lower hinge bar of which the terminal eye 29 is engaged with the lower hinge pin extends between the tie bars at the hinged end of the gate and through a notch or seat 30 in a seat plate 31 arranged transversely spanning the interval between said tie bars at the hinged end of the gate, said lower hinge bar extending under and therefore bearing upward upon the seat plate or in the reverse relation thereto as compared 105 with the upper hinge bar and its seat plate 23. The inner or free end of the lower 110

hinge bar extends through an opening in a guide 32 spanning the interval between two of the longitudinal members or boards of the gate and provided with ears 33 which are bolted as at 34 to said boards. The lower hinge bar is perforated at 35 for engagement by a pin 36 to determine the distance between the hinged end of the gate and the hinge pin.

10 It will be obvious from the foregoing description that the free end of the gate may be tilted upward to any desired extent by the selective engagement of the notches 24 of the upper hinge bar with the anchor pin 25, and that longitudinal adjustment of the gate can be effected by bodily movement of the gate with relation to both the upper and lower hinge bars, the engagement of the securing pin 26 with different openings 35 of 15 the lower hinge bar being effected to agree with the engagement of the anchor pin 25 with the notches 24 of the upper hinge bar.

In order to facilitate the vertical adjustment of the free end of the gate there is 20 preferably employed a trip or lift 37 consisting of a lever pivotally mounted at 38 upon one of the longitudinal members of the gate and having its upper arm provided with a transverse lift pin 39 engaged with 25 the upper hinge bar near its inner or free end. Connected with the opposite arm of the trip or lift is an operating wire 40 extending as indicated to the free end of the gate so that it may be grasped by the operator and drawn to tilt the trip or lift to raise 30 the free end of the upper hinge bar out of engagement with one of the notches 24 to permit of either raising or lowering the free end of the gate.

40 From the foregoing description it will be observed that the bottom or lower hinge is of such a construction as to resist thrust toward the hinge post while the upper hinge embodies a bar which extends toward and 45 tensionally supports the free or swinging end of the gate, the connection or engagement of said bar with the gate being in the construction illustrated at or near the center of the length of the gate, as distinguished 50 from those structures in which the weight

of the free or swinging end of the gate is supported by means connected with the gate at or near its hinge end and which latter arrangement results in practice in permitting a sagging of the free or swinging end of the gate and a straining thereof in use, which is entirely eliminated with the construction herein described. The downward and outward extension of the diagonal brace 16 from the point of engagement of the upper hinge bar with the gate toward the free or swinging end of the gate serves to divert the tensional resistance of the upper hinge bar so as to afford a lifting effect upon the free end of the gate in the direction of the length of said brace 16.

55 While the preferred embodiment of this invention is shown and described it will be understood that minor changes in the details of construction and arrangement of parts may be resorted to within the scope of what is claimed without departing from the spirit of the invention.

Having thus described the invention, what I claim is:—

75 A gate including longitudinal and vertical bars, means securing said vertical bars to said longitudinal bars and to each other, a hinge bar connected with the upper edge of said gate, a hinge bar at the lower edge of said gate having openings therein and extending between a pair of said vertical bars, a plate connecting said pair of vertical bars and engaging said hinge bar, a block 80 connecting a pair of said longitudinal bars, said block having an opening therethrough through which said second named hinge bar extends, and a pin selectively engageable in the openings in said second named hinge bar and engageable with the rear pair of vertical bars to resist thrusts of the gate toward the gate support and to compensate for changes in adjustment of the gate.

85 In testimony whereof I affix my signature in presence of two witnesses.

EDWARD E. ANSON.

Witnesses:

GUY ANDREW,
LAWRENCE J. GRAY.
